UNITED STATES PATENT OFFICE

161,541

REARVIEW MIRROR OR SIMILAR ARTICLE FOR MOTOR VEHICLES

Lowell F. Sarnes, Birmingham, Mich., assignor to
George C. Knight Company, Oak Park, Mich.,
a corporation of Michigan

Application June 4, 1949, Serial No. 3,043

Term of patent 14 years

(Cl. D14—6)

To all whom it may concern:

Be it known that I, Lowell F. Sarnes, a citizen of the United States, residing at Birmingham, Oakland County, Michigan, have invented a new, original, and ornamental Design for a Rearview Mirror or Similar Article for Motor Vehicles, of which the following is a specification, reference being had to the accompanying drawing, forming a part thereof.

Fig. 1 is a side view of a rearview mirror or similar article for motor vehicles embodying by invention.

Fig. 2 is a top plan view thereof.

Fig. 3 is an end elevational view thereof.

Fig. 4 is a sectional view taken substantially on the line 4—4 of Fig. 1, looking in the direction of the arrows.

The characteristic features of my design reside in the portions shown by means of full lines in the drawing.

I claim:

The ornamental design for a rearview mirror or similar article for motor vehicles, substantially as shown and described.

LOWELL F. SARNES.
